Attorney

UNITED STATES PATENT OFFICE.

CHARLES M. LAWRENCE, OF BROOKLYN, NEW YORK, ASSIGNOR TO UNDERWOOD TYPE-WRITER COMPANY, OF NEW YORK, N. Y., A CORPORATION OF DELAWARE.

TYPEWRITING MACHINE.

Application filed June 24, 1925. Serial No. 39,170.

To all whom it may concern:

Be it known that I, CHARLES M. LAWRENCE, a citizen of the United States, residing in Brooklyn Borough, in the county of 5 Kings, city and State of New York, have invented certain new and useful Improvements in Typewriting Machines, of which the following is a specification.

The present invention relates to glare-preventing shades for windows arranged in 10 sound-deadening cabinets for observing typing on the platens of typewriting machines enclosed in said cabinets, and it may be especially serviceable where glare in the 15 cabinet windows is caused by light coming from the right or left of the windows.

According to the present invention, provision is made of a shade including an opaque body-plate slidably mounted on a 20 grooved track fastened on the usual cover of a sound-deadening cabinet for a typewriting machine in the rear of the usual window for observing typing on the platen of the machine. An opaque wing may be hinged 25 to each end of the body-plate and be arranged with a flexible, downwardly-extending wire having a rubber shoe-element for engagement with the glass window, whereby the wings may be held in several different 30 operative positions to intercept glare causing light rays from the right or left of the window.

Other features and advantages will hereinafter appear.

35 In the accompanying drawings,

Figure 1 is a partial end view of a sound-deadening cabinet for a typewriting machine, and having the adjustable shade of the present invention attached thereto.

40 Figure 2 is a partial front view, on a reduced scale, of the same.

Figure 3 is a plan view, on a reduced scale, of the same.

45 Figure 4 is a diagrammatic plan view of the adjustable shade of the present invention in place on a sound-deadening cabinet, illustrating a certain way a shade can be used.

50 A sound-deadening cabinet 9, for a typewriting machine 10, is shown as including a body-part 11 having a cover 12 fastened thereto by hinges 12^a. The cabinet 9 may have an outer casing and the usual interior lining (not shown) of a sound-absorbing material. The cover 12 may have the usual window-opening 13 closed by a transparent

glass plate 14, through which the operative may observe the typing on the platen of the machine 10. To prevent objectionable glares in the window-glass 14 or reflections therefrom to the eyes of the operative, a shade 15, having a substantially-rectangular opaque body-portion 16 and opaque wings 17 and 18 hinged at the left and right ends thereof, is provided. The body-portion 16 may be adjustably mounted on two legs 19 60 having springy foot-portions 20 arranged to slidably engage with a grooved metal track 21 fastened on the cover 12 by screws 22 at the rear of the window-opening 13.

The track 21 may have a plane base 23 70 and two inwardly-inclined flange-members 24 which may form, with the base, a substantially dovetail recess. The springy foot-portions 20 will preferably be bent to fit snugly in the dovetail recess element of the 75 track 21, with sufficient pressure against the inclined flanges 24 to hold the shade 15 securely in operative position substantially perpendicular to the plane of the cover 12. The shade may be readily moved to the right 80 or left on the track 21 by the operative, but the pressure of the foot-portions 20 in the dovetail recess will prevent accidental movement of the shade sidewise.

85 The wings 17 and 18 may be connected to the body-portion 16 by piano-type hinges 25 about pins 26, so as to provide close connections without cracks or openings, through which light rays may pass. The wings may be especially advantageous when arranged 90 as illustrated in Figures 2 and 3, whereby one wing may intercept glare-causing light rays coming from the right and the other wing may intercept light rays coming from the left.

95 Each of the hinged wings 17 and 18 may be securely held at any desired angle with the body-portion 16 by means of a flexible wire catch-piece 27, having its upper end fastened to its wing by a screw 28, and its lower end provided with a short, tubular rubber shoe or sleeve 29 for engagement on the glass plate 14. The shoes 29 may be arranged to engage on the glass plate 14 with a pressure sufficient to hold the wings against accidental 105 movement, but will permit the operative to swing the wings readily to any desired position. The catch-pieces 27 also serve as braces to help hold up the weight of the wings 17 and 18, thereby lessening consider- 110

ably the overturning strain from the shade 15 which would have to be wholly resisted by the foot-members 20 engaging in the dovetail recess of the track 21, were the 5 foot-pieces omitted. When the glare-producing light comes squarely from the rear of the cabinet, both wings 17 and 18 may be swung entirely, or nearly, in line with the central body-part 16, as indicated in Figure 4.

The catch-pieces 27 will preferably be made flexible enough to permit their lower rubber-covered ends to be readily sprung high enough to clear the top of the cover 12, 15 so that both foot-portions 20 of the shade 15 may be slid off the track 21, at one end thereof, and the shade 15 removed when not needed.

Variations may be resorted to within the 20 scope of the invention, and portions of the improvements may be used without others.

Having thus described my invention, I claim:

1. The combination with a sound-deadening cabinet for a typewriting machine, said cabinet having a body-part and a cover hinged thereto provided with a glass window for observing typing on the platen of said machine, of a grooved track mounted 25 on said cover in the rear of said window, a light-intercepting shade slidably mounted on said track and having a body-portion, wing-portions hinged to each end thereof, and spring-pressed means for holding said 30 wing-portions in different operative positions.

2. The combination with a sound-deadening cabinet for a typewriting machine, said cabinet having a body-part and a cover hinged thereto provided with a glass window for observing typing on the platen of 40 said machine, of a grooved track mounted on said cover in the rear of said window, and a light-intercepting shade, having a body-portion, slidably mounted on said track, a wing-portion hinged to each end of 45 said body-portion, and individual means for holding each wing-portion in different operative positions, said means including a downwardly-extending flexible wire catch-piece having its upper end fastened to one of said wings and its lower end provided with a rubber shoe-element for frictional engagement on said glass window.

3. A glare-preventing means for a sound-deadening cabinet for a typewriting machine, said cabinet having a glass window for observing the typing on the platen of the machine, said means including a shade 55 substantially perpendicular to the plane of said window mounted in the rear thereof and arranged for being slid in operative position along said window to the right or left.

4. A means for preventing glare in the 60 glass window arranged in a sound-deadening

cabinet for a typewriting machine for observing typing on the platen of said machine, said means including a grooved track mounted on the top of the cabinet in the rear of said window, and a shade substantially perpendicular to the plane of said window mounted on two foot-elements arranged to slidably engage with said grooved track, whereby said shade may be held in different operative positions with respect to 75 said window.

5. The combination with a sound-deadening cabinet for a typewriting machine, said cabinet having a lower body-part and a cover hinged thereto provided with a glass 80 window for observing the typing on the platen of said machine, of a grooved track fastened on said cover adjacent the rear side of said window, and an opaque shade arranged for preventing glare-causing light 85 rays from striking said window and slidably mounted on said track.

6. The combination with a sound-deadening cabinet for a typewriting machine, said cabinet having a lower body-part and a cover 90 hinged thereto provided with a glass window for observing the typing on the platen of said machine, of an opaque shade arranged for preventing glare-causing light 95 rays from striking said window and mounted on means movable to the right or left on said cover in the rear of said window.

7. The combination with a sound-deadening cabinet for a typewriting machine, said cabinet having a lower body-part and a cover 100 hinged thereto provided with a glass window for observing the typing on the platen of said machine, of an opaque shade having a substantially rectangular body-portion and a wing-portion hinged to each 105 end thereof arranged for preventing glare-producing light rays from striking said window and adjustably mounted on said cover in the rear of said window for movement to the right or left.

8. The combination with a sound-deadening cabinet for a typewriting machine, said cabinet having a lower body-part and a cover hinged thereto provided with a glass window for observing the typing on the platen of said machine, of an opaque shade having a substantially rectangular body-portion and a wing-portion hinged to each end 115 thereof arranged for preventing glare-producing light rays from striking said window and movably mounted on said cover in the rear of said window, said wing- 120 portions having downwardly-extending flexible catch-pieces arranged for engagement with said glass window to hold the wing-positions in different desired operative positions with respect to said body-part.

9. A glare-preventing shade for a window in the cover of a sound-deadening cabinet 125 for a typewriting machine, said cabinet in-

cluding a grooved track mounted on said cover in the rear of said window, an opaque plate shorter than said window and substantially perpendicular to the same mounted on 5 said track, an opaque wing at each end of said plate having a light-proof hinged connection thereto, and a wire catch-piece fastened to each wing and extending downwardly therefrom having a rubber covered 10 lower extremity for engagement with said glass window, each of said catch pieces being arranged to carry part of the weight of the hinged wing to which it is fastened.

10. Means for preventing glare in a glass 15 window of an inclined top of a sound-deadening cabinet for a typewriting machine, said means including a track arranged with a dovetail recess-element and mounted in the rear of said window, an opaque shade 20 substantially perpendicular to said top, said shade having flexible foot members arranged for slidable engagement in the recess-element of said track to help hold said shade up in operative position, and wire means 25 fastened to said shade arranged to engage with said window for holding said shade against accidental lateral movement on said track and to assist in holding said shade in its operative position.

11. A detachable glare-preventing means 30 for a glass window in a sound-deadening cabinet for a typewriting machine, said means including a grooved track mounted on said cabinet in the rear of said window, and an opaque shade substantially perpendicular 35 to the plane of said window and provided with two foot-members arranged to slidably engage with said track to hold said shade in operative position, said track arranged to permit said shade-supporting foot-members 40 to be slid out of engagement therewith at either end thereof.

12. A detachable glare-preventing means 45 for a glass window in a sound-deadening cabinet for a typewriting machine, said means including a grooved track mounted on said cabinet in the rear of said window, an opaque body-part substantially perpendicular to the plane of said window, an opaque wing hinged to each end of said body-part, 50 and two foot-members arranged for supporting said body-part and slidably engaging with said track, said track arranged to permit said body-part-supporting members to be slid out of engagement therewith at 55 either end thereof.-

CHARLES M. LAWRENCE.
